(57) **CLAIM**

The ornamental design for a portable split refrigerator, as shown and described.

DESCRIPTION

FIG. 1 is a front elevation view of a portable split refrigerator showing our new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is an upper front perspective view thereof;

FIG. 8 is an upper front perspective view thereof in an open condition; and,

FIG. 9 is an upper interior perspective view thereof, shown in an open condition.

The broken lines are included for the purpose of illustrating portions of the portable split refrigerator that form no part of the claimed design.
